UNITED STATES PATENT OFFICE.

HENRY LEWIS, OF MCKENZIE, NORTH DAKOTA.

DESIGN FOR A STAND FOR SUPPORTING AN ELECTRIC LIGHT OR SIMILAR ARTICLE.

Application filed December 28, 1928. Serial No. 29,434. Term of patent 7 years.

To all whom it may concern:

Be it known that I, HENRY LEWIS, a citizen of the United States, residing at McKenzie, in the county of Burleigh and State of North Dakota, have invented a new, original, and ornamental Design for a Stand for Supporting an Electric Light or Similar Article, of which the following is a specification, reference being had therein to the accompanying drawings.

In the drawings:

Figure 1 is a perspective view of my stand, showing two sides thereof, while

Figure 2 is a perspective view of same, showing the remaining two sides.

What I claim is:

The ornamental design for a stand for supporting an electric light or similar article, as shown.

In testimony whereof I hereunto affix my signature.

HENRY LEWIS.
